UNITED STATES PATENT OFFICE.

CHARLES H. WOODS, OF DECATUR, ILLINOIS.

FARE BOX.

Application filed May 31, 1919. Serial No. 301,065.

To all whom it may concern:

Be it known that I, CHARLES H. Woods, a citizen of the United States, a resident of Decatur, in the county of Macon and State 5 of Illinois, have invented new and useful Improvements in Fare Boxes, of which the following is a specification.

This invention has reference to fare-boxes, and relates particularly to that type 10 of fare-box in which is deposited the coin, ticket or the like by a passenger on entering the street-car.

The invention has for one of its objects to provide a till or receiving receptacle re- 15 movably arranged in a container, and being provided with a closure normally retained in an open position, and assuming a closed position and automatically locked, during the movement of removing the till or 20 receiving receptacle from the container.

The invention has for a further object to provide a till or receiving receptacle with a slide-cover, and controlling mechanism including locking levers adapted to be 25 moved into locking relation with said cover upon tilting the dumping plate, and holding said cover during the movement of removing the till or receiving receptacle, whereby said cover will be automatically 30 closed and locked.

A further object of the invention is to combine with a till or receiving receptacle having a slide-cover, a plurality of locking levers arranged to have a locking relation 35 with said slide-cover, and a dumping-plate actuating means adapted to move the locking levers to operative position to prevent movement of the slide-cover during withdrawal of the till or receiving receptacle, 40 whereby the slide-cover may be closed and locked.

A further object of the invention is to provide a container with one hinged side wall; a till or receiving receptacle adapted 45 to be removed from and replaced within said container through the opening closed by said hinged wall, said till or receiving receptacle being provided with a slide-cover; a dumping plate; locking levers normally arranged to prevent movement of said 50 till or receiving receptacle and arranged to have movement to release the till or receiving receptacle proper, but to be brought into locking relation with said slide-cover, and means associated with the dumping plate 55 and movable therewith, adapted to move the

locking levers into locking relation with the slide-cover of the till or receiving receptacle, to hold said slide-cover during the withdrawal of the till or receiving receptacle from the container and closing and locking said slide-cover simultaneous with such withdrawal. 60

That the invention may be more fully understood, reference is had to the accompanying drawings forming a part of this specification, in which:

Figure 1 is a side elevation, partly in section, showing a fare-box with my invention embodied therein; 70

Figure 2 is a front elevation of the fare-box, partly in section, as the same would appear on the line 2-2 of Figure 1;

Figure 3 is a detail, partly in section, showing the parts in the position they would 75 be in, preparatory to the removal of the till or receiving receptacle;

Figure 4 is a view similar to Figure 3, except that the lid or slide-cover for the till or receiving receptacle has been closed and 80 locked during the movement of removing the till from the container;

Figure 5 is a perspective view of the till or receiving receptacle, with the lid or slide-cover open; 85

Figure 6 is a perspective view of one of two locking-levers, and

Figure 7 shows two opposite views of one of two bell-crank levers used in actuating the locking levers. 90

The fare-box comprises in the main, a container supporting a depository for the coins, tickets and the like, and separated by a dumping-plate; a till or receiving receptacle adapted to be removably housed in the container and having a lid or slide-cover which, when moved to a closed position, is locked, and controlling means for causing the lid or slide-cover to move to locking position as the till or receiving receptacle is being removed from the container. 95

The container.—This is preferably made in the form of an upstanding rectangular box 1, having four side walls, one of which is a door 2 hinged at 3 to the bottom of the container so as to be swung outwardly and down to allow for the removal and replacement of the till or receiving receptacle. A key-lock 4 is provided at the upper end of the door 2 that it may be locked when closed. 105

The container 1 is capped by a casting 5

formed with a hopper shaped inlet 6 and recesses or grooves 7 to receive the walls of the depository, and depending within the casting from its top wall is a hopper shaped neck 8, the front edges 9 of the side walls of which are off-set, for purposes which will become apparent. The bottom of the container has rails 10 on which the till or receiving receptacle slides and rests.

10 *The depository.*—This is also made preferably in the form of an upstanding rectangular receptacle 11 having the metallic corner pieces 12 seated in the grooves or recesses 7, and connecting the said corner pieces are the transparent side walls 13, preferably glass. The depository is capped by a casting 14, secured in place in any suitable manner, and off-set on said casting 14 and upstanding thereon is the preferably circular shaped neck 15 into which the coin, ticket or the like is deposited. Making the neck 15 circular in shape does away with the possibility of injuring a passenger's hand when depositing a coin, ticket or the like, which would be possible, had the same sharp corners, due to the lurching of the car. Suitably arranged in the depository 11 are a plurality of staggeredly arranged baffle-plates 16 with notched lower edges 17.

30 Normally lying across and closing the lower end of the hopper shaped inlet 6 of the casting 5 is a dumping-plate 18 which is suitably secured at its front side to a spindle 19 journaled in bearings 20 depending from the casting 5, and one end of said spindle passes out through one side of said casting and has secured to said protruding end the handle or crank-arm 21 to be grasped by an operator when it is desired 40 to tilt downwardly, said dumping-plate 18. A coil spring 22 wrapped or coiled about said spindle and with a part bearing against the lower face of said dumping-plate 18, and its ends bearing against a rod 23 secured 45 in the walls of the hopper shaped neck 8 acts to return the dumping-plate 18 to its closed position and normally hold it closed, except when tilted in the manner specified, which, as will be understood, is against the tension of said spring.

50 *The till or receiver receptacle.*—This is preferably a metallic box 24 which in shape conforms to the contour of the container 1 having a hand-hold 25 to be grasped by an operator when removing the same from the container, or replacing it. The upper end of the till or receiving receptacle is capped by a casting 26 formed with a dividing partition 27 extending the full width 60 of the casting, in one direction, and only approximately one-half way across in the other direction, so as to provide an opening 28 through which coins, tickets and the like may pass when entering the till or receiving 65 receptacle, and dumped by the dumping-

plate 18. The inner end of said partition is bent up, as at 29 to provide a stop, and other stops 30 are provided at the front side of said casting, see Fig. 5. In the opposite side walls of the casting 26 are provided longitudinal grooves 31.

75 32 designates a lid or slide-cover for closing the opening 28 providing communication to the interior of the till or receiving receptacle. This lid or slide-cover is slideable back and forth in the grooves 31 of the casting 27 and at its front has the depending plate 33 which abuts with the stop 29, when moved to a closed position, and abuts with the stops 30 when fully opened. 80 To the inner end of said lid or slide-cover is attached one part of a key-lock 34, the other or complementary part of which is secured to the casting 26. I have not detailed the lock structure, as any suitable 85 and reliable key-lock may be employed. It is intended, however, that when the lid or slide-cover moves to its closed position, the lock 34 will automatically lock, and the lid or slide-cover may not be moved to an open 90 position until the key is inserted to unfasten the lock.

95 The casting 26 at its opposite sides and at predetermined points in its length is provided with upstanding lugs 35, 35. The lid or slide-cover 27 at its opposite sides and at predetermined points, in its length is also provided with upstanding lugs 36, 36. The function of these lugs will be more fully explained.

100 *The controlling means.*—37, 37 designate locking levers fulcrumed on pins 38, on the opposite sides of the hopper shaped neck 8. The pins 38 pass through short curved slots 39 in the levers to permit said levers to 105 shift their positions, bodily, on said pins for reasons which will become apparent.

110 Each lever is formed with a preferably oval shaped lower edge 40 terminating in a heel 41 at or near the rear end and with a slot 42 near the front end, and projecting laterally from the upper edge, at a predetermined point near the front end is a shelf portion 43.

115 The normal position of the levers 37 is best seen in Fig. 1. Such position is maintained by springs 44, connected to the rod 23 and a rod 45 connecting the two levers 37, see Fig. 2, insuring their acting in unison. In the position shown in Fig. 1, the front 120 end of the levers 37 are raised, with their heels 41 lying down within the opening 28 leading into the till or receiving receptacle 24, and in front of a top wall portion 46 of the casting 26. It should be obvious 125 that, if it were possible to withdraw the till or receiving receptacle 24 from the container 1, the parts being in the position shown in Fig. 1, that the wall 46 would be stopped through engagement with the heels 130

41 on the levers 37, and that therefore, said levers must be moved to the position shown in Fig. 3, to permit the top of the till or receiving receptacle to ride under said levers.

5 As previously stated, it is impossible to withdraw the till or receiving receptacle 24 from the container until the locking levers 37 have been moved from the position shown in Fig. 1 to the position shown in Fig. 3, which will change the position of the heels 41 of said levers 37, raising such heels so that the till or receiving receptacle may ride therebeneath. This is accomplished by imparting rotational movement to the spindle 19 which will swing the short ends 48 of the bell crank levers 47 down into position where they will engage with the shelf portions 43 on such locking levers 37. Such engagement of the bell crank levers with the locking levers will move said last mentioned levers from the position shown in Fig. 1 to the position shown in Fig. 3. At the same time the slots 42 in the front end of said locking levers 37 are moved to a position embracing the lugs 36 on the lid or slide-cover 32 on said till or receptacle to hold the lid, during the removal of the till, and resulting in a locking of said lid, as it is believed will be understood.

Operation.—In operation with the parts shown in their normal positions, illustrated in Figure 1, a coin, ticket or the like deposited in the depository 11, and finally resting upon the dumping plate 18, may be transferred to the till, or receiving receptacle 24 upon the operator grasping the handle 21 and rocking the spindle 19, so as to move the dumping plate from that position shown in Figure 1, to the position shown in Figure 3; the coin, ticket or the like sliding off of the dumping plate and passing down through the opening 28 in the till or receiving receptacle and lodging on the bottom of said receptacle. This operation is continued from time to time, the dumping lid 18 being returned to its normal position after each operation, upon the operator releasing the handle 21, permitting the spring 22 to act to return the parts to the position shown in Figure 1.

We will assume that it is desirous of removing the till or receiving receptacle from the container 1. A key is inserted in the lock 4 to permit the hinged side 2 of the till to be swung outwardly and downwardly, so as to enable the operator to grasp the handle 25 of the till or receptacle 24 to withdraw it from the container.

60 As previously stated, it is impossible to withdraw the till or receiving receptacle 24 from the container until the locking levers 37 have been moved from the position shown in Figure 1 to that position shown in Figure 3, and to accomplish this result, the op-

erator must rock the spindle 19 so as to swing the short ends 48 of the bell crank levers 47 down into a position where they will engage with the shelf portions 43 on the locking levers 37, moving said levers from the position shown in Figure 1 to that position shown in Figure 3, which will change the position of the heels 41 of said levers 37 so that the till or receiving receptacle may ride beneath said locking levers, and at the same time, the slots 42 in the front ends of said locking levers 37 are moved downwardly so as to embrace the lugs 36 on the lid or slide-cover 32 on said till or receiving receptacle.

It is observed that the operation just described also oscillates the dumping lid 18 so that any coins, tickets or the like which are resting thereon, must be dumped into the till or receiving receptacle 24 with the final operation of placing the controlling parts in a position to permit the till or receiving receptacle to be removed from the container.

With the parts in the position shown in Figure 3, the operator may withdraw the till or receiving receptacle from the container and during such operation, the lugs 35 may be withdrawn outwardly and from beneath the long ends 49 of the bell crank levers 47, while at the same time with the lugs 36 on the lid or slide-cover within the slots 42 of the locking levers, said lid or slide-cover is retained in a stationary position, while the body of the till or receiving receptacle is withdrawn to a position which will cause the lid or slide-cover to assume a closed position and be automatically locked, as shown in Figure 4.

To place a till or receiving receptacle in a container, it is obvious that the operator must necessarily rock the spindle 19 so as to elevate the long ends 49 of the bell crank levers 47 so as to permit the lugs 35 on the casting 26 to pass from beneath and to assume the position shown in Figure 1. In this position, the long ends 49 of the bell crank levers 47 will be dropped into a position in front of said lugs 35, which, together with the heels 41 of the locking levers, will lock the till or receiving receptacle in position in the container.

With the construction and arrangement of the controlling means as shown, and the construction of the lid or slide-cover for the till or receiving receptacle and the particular hopper shaped neck 8 of the casting 26, it is impossible for the parts to be tampered with in any way before the removal of the till or receiving receptacle, which would give any one access to the interior of the device, and that the till or receiving receptacle cannot be removed without first oscillating the dumping plate 18 to insure the deposit of coins, tickets and the like into the

till or receiving receptacle, and that during the operation of sliding the till or receiving receptacle from the container, the lid or slide-cover is automatically moved to a locking position and the same locked.

It is observed that the depending hopper shaped neck 8 has but a short front wall 9^a, and that the side walls 9 are off-set so as to form a stop against which the lugs 36 on the lid or slide cover abut when the till is inserted into the container. With the rods 23 and 45 arranged as they are, and it being necessary to drop the plate 18 to lift the long arm 49 of the bell crank levers 47 before the till may be moved bodily, it is obvious that there is little or no chance for rifling the till during its removal or withdrawal from the container.

While I have shown and described the present invention as being applicable to one form of fare-box, it is obvious that the invention may be applied equally as well to other coin containers, and I, therefore, do not wish to be confined to the disclosure except as claimed in the appended claims; nor do I wish to be confined to the specific details of construction disclosed except as specifically claimed; as it is obvious that various changes may be made without departing from the spirit and scope of the invention.

What I claim is:

1. In a fare-box, in combination, a casing, a till or receiving receptacle having an opening in its top and a closure therefor, means to lock the till within said casing, levers arranged to alternately lock the till in receiving position and the closure against movement when the till is released and during movement thereof, whereby said closure assumes a closed and locked position on the till, a hand crank, and means operated thru the movement of said crank to engage and actuate said levers to release said till.

2. In a fare-box, in combination, a casing, a till or receiving receptacle having an opening in its top and a closure therefor, means to lock the till within said casing, lugs on said closure, levers having slots to embrace said lugs, said levers arranged to alternately lock the till in receiving position and the closure against movement when the till is released and during movement thereof, whereby said closure assumes a closed and locked position on the till, a hand crank, and means operated thru the movement of said crank to engage and actuate said levers to release said till.

3. In a fare-box, in combination, a till or receiving receptacle having an opening in its top and a closure therefor, lugs on the top of said till, lugs on the closure, lever arms normally positioned in front of said lugs on the top of the till, levers having slots which receive the lugs on the closure to hold the latter against movement during

movement of the till body, whereby the closure assumes a closed and locked position, a hand crank, and means operated thereby for moving the slotted levers to engaging position with the closure lugs, when said first mentioned lever arms are moved from in front of the lugs on the till body.

4. In a fare-box, in combination, a container, a depository thereabove, a till or receiving receptacle for the container having an opening in its top and a closure therefor, a dumping plate controlling communication between the depository and the till, lugs on said closure, levers normally holding the till body against movement and having slots to receive said lugs to hold the closure against movement of the till body, whereby the closure assumes a closed and locked position, a hand crank and means operated thereby for dumping said plate and moving said levers to release the till body and engage said lugs.

5. In a fare-box, in combination, a container, a depository thereabove, a till or receiving receptacle for the container having an opening in its top and a closure therefor, a dumping plate controlling communication between the depository and the till, lugs on said closure, a pair of pivoted levers having heels normally lying within the opening in the till to lock the till against movement and having slots to embrace the lugs to hold the closure against movement of the till body, whereby the closure assumes a closed and locked position, a hand crank, and levers associated with said crank and operated thereby to actuate said pivoted levers to raise the heels and lower the slots to embrace the said lugs, said crank also arranged to operate said dumping plate simultaneously with the actuation of said levers.

6. In a fare-box, in combination, a container, a depository thereabove, a hinged dumping plate therebetween, a till or receiving receptacle removably located in said container having an opening in its top and a closure therefor, lugs on the body of said till, lugs on said closure, levers normally holding the till body against movement and having slots to embrace the lugs on the closure to hold the same against movement of the till-body, whereby the closure assumes a closed and locked position, bell-crank levers having parts normally disposed in front of the lugs on the till-body and other parts to engage said first mentioned levers to release the till body and move them to embrace the lugs on the closure, and a hand crank for actuating said bell-crank levers.

7. In a fare-box, in combination, a till or receiving receptacle having an opening in its top and a closure therefor, lugs on said closure, levers normally holding the till body against movement and having slots to embrace said lugs to hold the closure against

movement of the till body, whereby the closure assumes a closed and locked position, means yieldingly holding the said levers in disengaged relation with said lugs and in locking relation with the till body, a hand crank, and means operated thereby for moving said levers to release the till body and embrace said lugs.

8. In a fare-box, in combination, a container, a despository thereabove, a hinged dumping plate therebetween, a door in one side wall of said container hinged so as to be swung outwardly and downwardly, a till or receiving receptacle removably located in said container and having horizontal movement when removed and replaced, said till having a top opening and a closure therefor, levers to hold the till body against movement, said levers also arranged when moved to release the till body, to be moved into holding engagement with said closure, levers associated with the dumping plate for actuating the closure holding levers when the dumping plate is moved, a hand crank operating said dumping plate and associated levers.

9. In a fare-box, in combination, a container having a hinged side door, a cap for said container having a hopper inlet and an interiorly arranged hopper shaped neck, a dumping plate hingedly arranged to close the bottom of the hopper inlet, a till or receiving receptacle adapted to have position in the container and having an opening in the top thereof normally below the hopper shaped neck, a slide-cover on said till to close said opening, levers pivoted to the hopper shaped neck normally holding the till body against movement and arranged when moved from such holding position to be moved to a position to hold the cover against movement during the movement of the till, whereby the cover assumes a closed and locked position, a hand crank to dump the dumping plate, and levers associated with the dumping plate to actuate said first mentioned levers to release the till body and to engage said cover.

In witness whereof, I have hereunto affixed my hand this 16th day of May, 1919.

CHARLES H. WOODS.
